UNITED STATES PATENT OFFICE.

FRANCIS CECIL PARDON, OF NEW YORK, N. Y.

GAS BURNER.

Application filed November 8, 1926. Serial No. 147,119.

The object of this invention is to provide an attachment for gas burners by which, when the burner is not to be used, the flame will be automatically reduced, and also to provide means whereby if it be desired to maintain the flame for a protracted period the reduction of the same may be prevented without requiring the attention of the user of the device. The invention is designed more particularly for use in dental laboratories but it is, of course, adapted for use in other fields. One embodiment of the invention is illustrated in the accompanying drawing, and the invention resides in certain novel features which will be particularly pointed out in the claims following a detailed description.

In the drawing:

Figure 1 is a side elevation of a Bunsen burner having my invention applied thereto;

Fig. 2 is an elevation of the device viewed at a right angle to Fig. 1, and

Fig. 3 is a detail section on the line 3—3 of Fig. 1.

The burner shown at 1 is an ordinary Bunsen burner fed by a pipe 2 leading from any convenient source of supply. The burner is mounted upon a base 3 of sufficient area to support the burner in a stable manner so that the liability of the device to tip over will be avoided. Where circumstances permit, the burner may be mounted upon a fixed support so that all possibility of accident will be eliminated.

In carrying out the present invention, there is secured about the burner, adjacent the upper end thereof, a bracket 4 having an arm 5 projecting laterally from the burner and formed with an eye or opening whereby it may guide a standard or rod 6 which is disposed at the side of the burner and has its upper end formed into or equipped with a laterally disposed rest 7, as shown. The lower end of the rod 6 is pivotally attached to one end of a lever or rocking arm 8 which is secured to the end of the valve stem 9 which controls the flow of gas through the burner. This arm or lever in the present instance is shown as inserted diametrically through the end of the valve stem but it may be secured thereto in any other manner which will have the required permanence. A contractile spring 10 is engaged with the end of the lever 8 more remote from the rod 6, and this spring is

attached to the base 3, as shown in Figs. 1 and 2, so that it tends constantly to pull down upon the lever and maintain the same in the position shown in full lines in Fig. 1 with the standard or rod 6 elevated. Fitted about the body of the burner, below the cut-off valve therein so as to be held frictionally in a set position, is a split collar 11 by which is carried an outwardly and upwardly extending stop arm 12 which projects below the lever 8 and across the path of movement of the same so that it will be engaged by said lever when the same is actuated by the spring 10. If the collar 11 be shifted about the body of the burner so that the stop 12 is disposed adjacent the valve stem or center of movement of the lever, the lever may swing to the limit of its movement, as shown in Fig. 1. If, however, the collar 11 be shifted about the burner so as to swing the stop 12 to a point more remote from the valve stem or the center of movement of the lever, the oscillation of the lever will be more restricted inasmuch as the end of the lever will impinge against the stop as the lever swings downwardly and, consequently, it will be prevented from swinging through an arc of the extent indicated by the full and dotted lines in Fig. 3.

Normally, the rod 6 and the rest 7 are held in their elevated positions and there is a very low flame maintained in the burner. If an operator desires to heat a tool or to warm wax or do any other act which in laboratory practice requires the application of heat, he merely presses downwardly upon the rest 7 so that the rest and the rod 6 will be depressed and the lever 8 rocked to the position indicated by dotted lines in Fig. 1, thereby turning the cut-off valve so as to permit an increased flow of fuel through the burner and, consequently, augmenting the flame. In common practice, the use of the burner is required for only a few seconds at any one time but the periods of use are very frequent. If the flame be permitted to play at its extreme height at all times, there will be an uneconomical use of the gas as well as an undesirable heating of the air surrounding the burner, and if the flame be entirely extinguished after each period of use and the burner re-lighted every time its use is desired, there is obviously a great loss of time. By the use of the present device, the flame is automatically increased when the operator presses upon

the rest 7, and frequently the tool may be merely placed upon the rest so that its weight will overcome the force of the spring 10 and hold the work in the proper relation to the flame which will be increased by the turning of the cut-off valve in an obvious manner. When the tool is removed, the spring 10 will automatically restore the parts to the normal position and reduce the flow of fuel. If, for any reason, it be desired to maintain the full flow of the gas or a lesser working flow for any considerable period, the stop 12 is shifted as above described so that it will prevent the movement of the lever 8 and the valve to the cut-off position, thereby maintaining the flame at the desired intensity while the operator may attend to some other duties.

The device is exceedingly simple and may be easily applied to any burner without interfering with the ordinary use thereof and without entailing a burdensome expense while its use will result in a pronounced reduction in the cost of the fuel consumed in the burner. Moreover, it will facilitate the work performed by the users of the burner.

Having thus described the invention, I claim:

1. The combination with a gas burner, and its cut-off valve, of a lever secured to and extending across the stem of the valve, a contractile spring attached to one end of the

lever whereby to maintain said end of the lever normally in a lowered position, a rest 35 carried by the opposite end of the lever and rising therefrom alongside the burner, and a bracket secured upon the upper portion of the burner and having a laterally projecting guide arm engaging around the 40 rest.

2. The combination with a gas burner, and its cut-off valve, of a lever secured to the stem of the valve, a rest carried by one end of the lever, yieldable means acting upon the other end of the lever to move the valve toward cut-off position, and a stop mounted upon the burner shiftable about the same adjacent the cut-off valve and extending 45 across the path of movement of the lever to limit the movement of the lever toward cut-off position.

3. The combination with a gas burner, and its cut-off valve, of a lever secured to the stem of the valve, yieldable means acting 55 on the lever to move the same toward cut-off position, a rest carried by the lever, a collar frictionally held upon the burner below the cut-off valve thereof and shiftable about the burner, and a stop arm projecting laterally from said collar across the path of movement of the lever whereby to variably limit the movement of the lever toward cut-off position.

In testimony whereof I affix my signature.
FRANCIS CECIL PARDON. [L. s.]
